UNITED STATES PATENT OFFICE.

MARTIN WALTHER, OF OSLO, NORWAY, ASSIGNOR TO DET NORSKE AKTIESELSKAB FOR ELEKTROKEMISK INDUSTRIE OF NORWAY, OF OSLO, NORWAY.

DISTANCE HANDLING OF ELECTRODES.

Application filed November 4, 1925, Serial No. 66,794, and in Norway November 7, 1924.

The electrode packets previously used in the big electric smelting furnaces for carbide and ferro-alloys have now gradually been replaced by the so-called selfbaking continuous electrodes which are made at the place where they are used. These electrodes are never removed from the smelting furnace but are lowered through the electrode holder when the working end of the electrode below the holder becomes too short.

As these electrodes may weigh up to 10 tons very strong electrode holders are required, having powerful pressing or gripping members to keep the electrode in place and preventing it from sliding uncontrolled through the holder during its use.

I have now found that the handling of such electrodes by means of a simple arrangement may be effected from a place at some distance from the furnace itself, said place not being subjected to the intense heat from the furnace.

Hereby firstly a greater safety for the workmen is attained, possible accidents as for instance drop of the electrode whereby glowing metal or carbide is splashed around causing no danger.

Secondly increased production is attained as it is possible to lower the electrode during its use without breaking the current.

The distance-handling may be carried out in many different ways, all according to the nature of the holder. Common to them all is one or more mechanical connection-members between the mechanism pressing the electrode tight in the holder and the place from which the distance-handling is effected.

Generally it will be advantageous to effect the distance-handling from the tamping room arranged above the furnace and in which the building up of the electrode is carried out. This room is always accessible during the use of the furnace and care is taken to keep the temperature of this room low by means of ventilation, cooling of the floor or the like. When no closed tamping room is arranged, the electrodes are at least led through a tamping platform which forms a shield against the radiation heat from the furnace.

The handling is, however, not limited to the place where the electrode is built up and according to my present invention I may effect the handling from any other convenient place.

In the drawings forming part of this application

Fig. 1 represents an elevational view, partly in section, illustrating the invention.

Fig. 2 represents an elevational view of one half of an electrode equipped with a modification form of the invention.

Fig. 3 represents a horizontal section, with parts broken away, of Fig. 2.

Fig. 4 represents a view similar to Fig. 2 of another form, parts being broken away and shown in section.

Fig. 5 represents a view similar to Fig. 3 of the form shown in Fig. 4.

Fig. 6 represents a view similar to Fig. 4 of still another form of the invention.

Fig. 1 is an elevational view, partly in section showing an electrode provided with a mechanism for distance-handling, 5 is the electrode, 6 is a platform protecting against heat from the furnace and above which the tamping takes place. 7 is a worm wheel driving the shaft 8 when set in motion by means of the wheel 9. The shaft 8 is movable in threads 10 and registers with the lever 11 movable around the tap 12 its other end pressing against the member 14 which again presses against the electrode gripping member 15 thus keeping the electrode in place. By opposite turning of the wheel 9 the electrode holder may again be loosened. All handling of the holder may thus be carried out from the tamping platform.

Fig. 2 illustrates a modified form of my invention showing an elevation of one half of an electrode in which the shaft 8 is moved in the same way as in Fig. 1, but due to its rotation moves the levers 16 and 17 as shown in Fig. 3 which is a section through Fig. 2 at the line *a*—*a*. The levers are movable around the taps 18 and 19 and engage with the members 14 which again press against the electrode gripping member 15.

Fig. 4 shows an elevation of one half of an electrode, partly shown in section, in which the shaft 8 by means of its rotation drives a worm wheel 20 which by means of threads will move the member 14 forwards or backwards.

Fig. 5 is a section through Fig. 4 at the line *b*—*b*.

Fig. 6 shows an elevation of one half of an electrode, partly shown in section, in which the shaft 8 moves a lever 21 by means of screw-threads 22. The lever is movable

around the tap 23 and by its movement presses the member 14 in or out.

In all drawings the same numbers refer to the same or corresponding parts.

5 As will be understood from above the invention may be carried into effect in many different ways and is not limited to above examples which only illustrate a few practical applications. The arrangement may of 10 course also be employed with usual electrodes of same dimensions as the continuous electrodes and will then afford the same advantages to the workmen.

What I claim as new and desire to secure 15 by Letters Patent of the United States is:

1. Arrangement for handling of selfbaking electrodes for electric furnaces comprising a tamping room arranged above the furnace and protected from the heat of the latter, a holder for the electrode, holder engaging means located below the room and adjacent the holder, a movable shaft extending into the room, means located in the room for actuating such shaft, and means operable by 25 the shaft for actuating said holder engaging means.

2. Arrangement for handling of electrodes for electric furnaces comprising a room protected from the heat of the furnace, a holder 30 for the electrode, a shaft terminating at one end adjacent the holder, means located in said room for operating said shaft, means for tightening and loosening said holder, and means connecting said tightening and loosening 35 means with the adjacent end of said shaft and operable by the latter for actuating said tightening and loosening means.

3. Arrangement for handling of selfbaking electrodes for electric furnaces comprising a room protected from the heat of the furnace and into which the electrode extends, a holder for the electrode, a rotatable shaft 40 extending to the outside of said room, means located in said room for operating said shaft, means for actuating the holder, and lever 45 mechanism interposed between said shaft and holder actuating means for operating the latter from the shaft.

4. Arrangement for handling of selfbaking electrodes comprising a room protected 50 from the heat of the furnace and in which the electrode is built up, a rotatable shaft, means located in the room for rotating said shaft, an electrode holder, holder engaging means located outside of the room and movable toward and away from the electrode, and means for translating the rotary movement of the shaft to movement of said holder engaging means toward and away from the electrode. 55

5. Arrangement for handling of selfbaking electrodes for electric furnaces comprising a tamping room in which the electrode is built up, an electrode holder located outside of said room, holder engaging means movable 60 bodily toward and away from the electrode, a shaft extending into the room at one end and terminating at its other end adjacent the holder, means located in the room for rotating said shaft, and means interposed between the holder and the adjacent end of the shaft 65 for translating the rotary movement of the shaft to movement of the holder engaging means toward and away from the electrode. 70
